[57] **CLAIM**

The ornamental design for a fish lure, substantially as shown.

DESCRIPTION

FIG. 1 is a perspective view of a fish lure embodying the present design;

FIG. 2 is a top plan view of the fish lure shown in FIG. 1;

FIG. 3 is a front elevational view;

FIG. 4 is an elevational view of the side of the fish lure opposite that seen in FIG. 1;

FIG. 5 is a rear elevational view; and

FIG. 6 is a bottom elevational view.
